CATHODE-RAY OSCILLOGRAPH

William A. Geohagan, New York, N. Y., assignor
to Allen B. Du Mont Laboratories, Inc., Pas-
saic, N. J., a corporation of Delaware

Application January 4, 1940, Serial No. 312,358

3 Claims. (Cl. 171—95)

My invention relates to improvements in cathode-ray tube oscilloscopes.

In the various cathode-ray tube oscilloscopes proposed heretofore, condenser coupling from the final amplifier to the deflection plates of the cathode-ray tube is employed, and positioning of the pattern on the fluorescent screen of the cathode-ray tube is accomplished by applying direct voltages or fixed potentials of D. C., to the deflection plates through a high resistance. While this method of positioning is satisfactory where good low-frequency response is not desired, when the time-constant of the coupling condenser and the resistance through which the positioning voltage is applied is large enough for good low-frequency response, say to one cycle per second, the positioning becomes so sluggish as to be objectionable, and often a period of many seconds elapses before a pattern whose position has been shifted reaches a new equilibrium position. This prior method of positioning, in fact, cannot be used at all where direct-current coupling is desired.

If there is employed direct coupling from the final amplifier to the deflection plates of the cathode-ray tube, where such amplifier may be of the type disclosed in my Patent No. 2,208,254, July 16, 1940, positioning may be accomplished by varying the bias on the input grid of the final stage. While this method of positioning provides certain advantages, it too is sluggish when good low-frequency response is desired.

With the foregoing in mind, it is one of the objects of my invention to provide an improved cathode-ray tube oscilloscope which not only embodies an amplifier having very low frequency response such as to a few cycles per second, but which also has the characteristic of instantaneous positioning of the cathode-ray spot or pattern on the fluorescent screen.

Other objects and advantages will hereinafter appear.

For the purpose of illustrating my invention, an embodiment thereof is shown in the drawings, wherein:

Figure 1 is a simplified, diagrammatic view of a cathode-ray tube oscilloscope constructed and operating in accordance with my invention;

Figs. 2 and 3 are partial views similar to Fig. 1, showing modifications;

Figs. 4, 4a, 4b, 5, 5a, and 5b are simplified, graphical views, illustrative of the principle or manner of operation of my improved oscilloscope; and

Fig. 6 is a simplified illustration of a modification.

With reference to Fig. 1, the numeral 1 designates any triode, tetrode, or pentode, and the numeral 2 designates a gas-glow tube of the type having the intrinsic characteristic which resides in substantially constant voltage drop across this tube over a relatively wide range of current variation. In the particular circuit shown in Fig. 1, 10 satisfactory results have been obtained by using for the tube 2 a conventional one-quarter watt neon bulb, without a resistor in the base. The tubes 1 and 2 and the parts or elements associated therewith constitute the positioning circuit, 15 designated generally by the reference numeral 3.

In this positioning circuit 3 the cathode 7 of the tube 1 is shown connected to tube 2 and resistance 8 in parallel. The resistance 8 is a potentiometer to which one end of the lead 12 to 20 an amplifier is slidably connected with a condenser 9 connected between this lead 12 and the upper end of the potentiometer 8. The plate of the tube 1 is connected to a positive potential above ground the same amount as the lower end of 25 resistance 8 is connected to a negative potential below ground so that the lead 12 can be varied from ground potential to potentials above and below ground potential.

The various parts comprising the final amplifier, designated generally by the reference numeral 4, have been designated by the same reference numerals as the respective parts in the same amplifier as disclosed in my copending application referred to. This amplifier embodies 30 the two tetrode tubes 10 and 11. The signal or wave-form to be investigated is applied to the control grid 14 of the first tube 10.

When a positive signal is applied to the control grid 14 of the first tube 10, its plate and 40 screen-grid current tend to increase, making its cathode 15 more positive and its plate 16 and screen-grid 17 less positive. Any increase in the positive potential of the cathode 15 of the first tube 10 applies also to the cathode 18 of the second tube 11 since these two cathodes are connected together. Any such increase in positive potential on the cathode 18 will tend to reduce the plate and screen-grid currents of tube 11 and make both its screen-grid 19 and its plate 20 more positive. Since the respective cathodes 15 and 18 of the tubes 10 and 11 are connected together, and since also the respective screen-grids 17 and 19 of the tubes are connected together, the changes induced on these elements in the second 55 tube 11 tend to nullify the original effect induced

on the corresponding elements of the first tube 18 by the input signal impressed on its control grid 14. That is, as the potential on the screen-grid 17 of tube 18 tends to be driven less positive by the action of the input signal through tube 10, the potential on the screen-grid 19 of the tube 11 tends to be driven more positive by the action of tube 11. Likewise, when the potential of the cathode 15 of tube 18 tends to be driven more positive by the action of tube 10, the potential of the cathode 18 of tube 11 tends to be driven less positive by the action of tube 11. Therefore, if the circuit constants be properly chosen, the potential changes on the respective plates 18 and 20 of the tubes 18 and 11 will be approximately equal in amount and opposite in direction, which is the desired effect.

The control grid 21 of the second tube 11 is grounded as shown, and is therefore held at a fixed potential. For other combinations of circuit components and constants, it may be desirable to hold the control grid 21 of tube 11 at a fixed potential above or below ground.

The plate output from the respective tubes 18 and 11 is applied, by the connections 22 and 23, across the deflection plates 24 of the cathode-ray tube 25. The input connection 12 may be connected to a pre-amplifier.

By means of the push-pull amplifier 4 shown, the average potential of each plate of the pair of vertical deflection plates can be kept approximately constant, thereby minimizing defocusing of the cathode-ray spot with deflection.

The amplifier 4 gives flat or constant response, and one hundred per cent response from D. C. or zero frequency to one megacycle.

The inductances 27 and 28 are not essential to the operation of the circuit, but when properly chosen values are employed, extend the high-frequency range to which the response is flat by effectively increasing the value of plate-load reactance at the proper rate to compensate for the increased effect of stray and output circuit-capacitance.

Pentodes may be used for the tubes 18 and 11, in lieu of tetrodes, in which case the suppressors would be connected directly to their respective cathodes.

Distinctive features of the push-pull amplifier 4 reside in the facts that the input signal, taken from the external source to be investigated, is applied directly to the control grid of one tube; that the respective output voltages of the two tubes 18 and 11 are equal in amplitude and opposite in phase; that the control grid 21 of the second tube 11 is held at fixed potential; that the signal developed on the second tube 11 is produced by the combined effects of tying the two screen-grids 17 and 19 together and of tying the two cathodes 15 and 18 together; that the two cathodes 15 and 18 are returned to ground or to the negative side of the high-voltage supply through a common resistor 29; and that the screen grids 17 and 19 are supplied from the positive side of the high-voltage supply through a common resistor 30. In other words, in my improved push-pull amplifier, coupling through a common screen-grid resistor 30 and through a common cathode resistor 29 is used to transfer a portion of the signal from the first tube 10 to the second tube 11, and to produce changes of equal amplitudes and opposite phase on the two plates 18 and 20.

In the operation of my improved oscilloscope, when the signal to be investigated is applied to

the grid 5 of the tube 4 by the connection 6 from the gain-control or from a preceding amplifier, it appears, slightly diminished in amplitude, on the cathode 7 of tube 4. Since the voltage across the positioning-control potentiometer 8 is held substantially constant by the gas-glow tube 2 connected in parallel relation to this potentiometer, the signal appears with equal amplitude at all points on the potentiometer, and the signal input to the final amplifier 4 is not, therefore, affected by changes in the positioning-control setting. The final fixed bias of the amplifier on which the signal is superimposed, however, will vary as the positioning control is moved. Therefore, the pattern may be positioned on the fluorescent screen 31 without affecting its amplitude. A condenser 9 may be used where high-frequency response is desired, to prevent frequency discrimination in the positioning control but due to its small size, it exerts no noticeable effect in slowing the positioning which is instantaneous.

A further advantage of my improved oscilloscope over the conventional condenser-coupled arrangement is illustrated in the drawings, in which Figs. 4, 4a and 4b illustrate the operating action in my improved oscilloscope, and Figs. 5, 5a and 5b illustrate the operating action in the conventional condenser-coupled arrangement of the prior art. That is, my improved oscilloscope effectively provides for handling signals several times as great as those which may be handled with prior art arrangements without distortion of the pattern on the fluorescent screen 31 of the cathode-ray tube.

With the pattern centered, it will appear undistorted with either arrangement, since the overload point of the amplifier is "off-screen." This will apply either when the size of the pattern is within the undistorted range R of the amplifier, as shown in Figs. 4 and 5, or when it exceeds the overload point of the amplifier, as shown in Figs. 4a and 5a. Considering a condition, however, where the pattern exceeds the undistorted output range R of the amplifier, and it is desired to study a portion of it without reducing the pattern size, as shown in Figs. 4a and 5a or 4b and 5b, the difference becomes apparent as follows: With the conventional method, adjustment of the positioning-control 8 will shift the pattern, but since the pattern size exceeds the overload point of the final amplifier 4, the edges of the pattern, when brought onto the screen 31, will be distorted, as shown in Fig. 5b.

With my improved method, however, positioning is accomplished by effectively superimposing a variable amount of D. C. on the input signal to the final amplifier. In this way, the overload point of the amplifier, as shown in Fig. 4b, remains off-screen even though the edge of the pattern is moved into view, and this edge is viewed undistorted.

Fig. 2 shows an arrangement wherein the positioning-control is fed directly from a preceding amplifier stage comprising a pentode 32, in which case the tube 4 in Fig. 1 is omitted.

In my improved oscillator, the final amplifier may be any D. C. coupled amplifier, either of the push-pull type for symmetrical deflection, or of the single-ended type for asymmetric deflection. Such amplifier may be connected directly to the deflection plates 24, or may be coupled to them by any means which provides D. C. coupling, such as through a neon bulb 33, as shown in Fig. 3.

From the foregoing, it will be seen that in my improved oscillator there is a positioning circuit such as 3, providing a positioning-control in the nature of a potentiometer across which a D. C. voltage exists when no signal is applied, this voltage remaining essentially constant at all times regardless of applied signal, each point on the potentiometer 8, however, varying in its voltage with respect to ground in a manner corresponding to the applied signal. Also, in my improved oscilloscope, use is made of a neon bulb or similar glow-tube across the positioning-control 8, to obtain the operating action as illustrated in Figs. 4a and 4b, as compared to that in the conventional method, as illustrated in Figs. 5a and 5b.

One of the broader aspects of my invention resides in application of a positioning-circuit such as 3 to a direct-coupled amplifier, such as 4, feeding the deflection plates of a cathode-ray tube. Such a combination permits good low-frequency response with instantaneous positioning-control, because of the direct-coupled feature.

The respective values of resistance, capacity and inductance designated in the drawings are given by way of example, and have been found to give satisfactory results, but may be changed to suit particular requirements.

In the claims, the term "tube" is used in the broad sense, and refers to a group or unit of elements such as a cathode, control grid, screen-grid and plate, and is intended to embrace a construction wherein two of such units or groups are contained in the same envelope, as illustrated by Fig. 6.

Modifications within the conception of those skilled in the art are possible without departing from the spirit of my invention or the scope of the claims.

I claim as my invention:

1. In a system of the character described, a cathode-ray oscilloscope, a deflecting plate amplifier-balancer circuit apparatus and a positioning circuit for said oscilloscope comprising

5 an amplifier tube with its output load circuit connected to its cathode, said load circuit consisting of a first resistive section and a second resistive section, said load circuit comprising means for passing desired signals undisturbed and comprising means by which variation of the direct current voltage output of the cathode resistor network causes positioning of the cathode-ray beam, said positioning circuit preceding and controlling said deflecting plate circuit.

2. In a system of the character described, a cathode-ray oscilloscope, a deflecting plate amplifier-balancer circuit apparatus and a positioning circuit for said oscilloscope comprising an amplifier tube with its output load circuit connected to its cathode, said load circuit consisting of a first resistive section and a shunt glow tube in parallel and a second resistive section, said load circuit comprising means for passing desired signals undisturbed and comprising means by which variation of the direct current voltage output of the cathode resistor network causes positioning of the cathode-ray beam, said positioning circuit preceding and controlling said deflecting plate circuit.

3. In a system of the character described, a cathode-ray oscilloscope comprising an amplifier connected to the deflection plates of said oscilloscope, means for applying signals to the input of said amplifier which signals are variable both positive and negative with respect to ground, whereby the amplified signals from said amplifier are caused to vary the potential of 35 said deflection plates both positive and negative with respect to ground, and means comprising a first impedance connected between the plate of a tube of said amplifier and a deflection plate of said oscilloscope, and a second 40 impedance connected between said deflection plate and a source of potential negative with respect to ground, said oscilloscope being linearly responsive to both direct and alternating voltage signals.

WILLIAM A. GEOHEGAN.
